UNITED STATES PATENT OFFICE.

WILLIAM F. BEASLEY, OF OXFORD, NORTH CAROLINA.

SHEET-METAL SEAL.

SPECIFICATION forming part of Letters Patent No. 377,662, dated February 7, 1888.

Application filed March 24, 1887. Serial No. 232,340. (No model.)

To all whom it may concern:

Be it known that I, WILLIAM F. BEASLEY, a citizen of the United States, residing at Oxford, in the county of Granville and State

5 of North Carolina, have invented certain new and useful Improvements in Sheet-Metal Seals; and I do declare the following to be a full, clear, and exact description of the invention, such as will enable others skilled in the art to which 10 it appertains to make and use the same, reference being had to the accompanying drawings, and to the letters and figures of reference marked thereon, which form a part of this specification.

15 My invention relates to a new and useful improvement in metallic seals for use in securing doors or openings of bonded warehouses, cars, &c.

It has for its object to provide a seal which 20 shall be made of a single piece, so constructed that when in position it must be defaced or mutilated to remove the same; and with this end in view my invention consists of a seal made in a single piece from sheet metal or 25 some suitable composition and having one end cut out to form a permanent "hasp" portion and having the body portion stamped or embossed with any desired design, as will herein-after be explained.

30 My invention further consists of a seal formed of a single piece of sheet metal or other composition, having one end cut out to form a permanent hasp and having the body stamped or embossed and perforated, as will be hereinafter explained.

35 My improved seal is intended for use with an improved seal catch or lock device which forms the subject-matter of a patent issued to Henry Clark, in which a sliding bolt provided 40 with a seal-slat and gateway is confined within a case, so that the seal cannot be removed after the bolt is fixed in position without cutting the seal; and for a more full and complete description of the same I refer to said patent.

45 In order that others may know how to make and use my improved seal, I will proceed to describe the same, referring by letters to the accompanying drawings, in which—

Figure 1 is a plan view of one of my improved seals, showing the body portion perforated or partially cut below the embossed

design; and Fig. 2 is a similar view with a different character of ring portion, and showing the body partially cut or perforated either below or across the design.

Similar letters denote like parts in both figures.

A is the seal, which is composed of thin sheet-brass or other metal, or some suitable composition. The upper end is preferably rounded, 60 and is cut away, as seen at B, to form a permanent half-ring, C, which is corrugated or has letters delineated thereon, or it may be smooth. On the body portion A any desired design, D, is formed in relief or intaglio, and a line of perforations extends entirely across the body to 65 form a separate coupon or check, F. This line of perforations may be made below the design, as seen in both figures of the drawings, or it may preferably be made across the design, as seen 70 at a a, Fig. 2.

The design D should be somewhat less in diameter than the width of the seal, in order that it may be impressed at varying distances from the edges thereof, and it may likewise 75 occupy varying relations to the ends of the seal, the object of this arrangement being that when the seal is perforated across the design to form a removable coupon or check, F, such coupon or check will not match with the body 80 of any other seal than the one from which it was removed, and in this way additional security is obtained.

Instead of any ordinary design being impressed upon the seal, any desired characters, 85 figures, or printed matter may be used.

The ring portion C being integral with the body portion, it cannot, when within a seal-slat or shackle of a bolt or lock, be cut for removal without exposing such fact.

In ordinary lead seals with wires the wires may be cut close to the seal and the seal replaced in position by embedding the cut end of the wires slightly within the lead. This method will temporarily disguise the fact that 95 the seal has been tampered with; but in the flat seal forming the subject of my invention it is obviously impossible to remove the same without exposure; and when I find it convenient to employ lead as the material out of which 100 to make the seal both ends of the wire will be fixed in it when molded, for this is the near-

est equivalent to a seal made of a continuous piece of metal.

What I claim as new, and desire to secure by Letters Patent, is—

- 5 1. A seal of metal or other composition formed of a single piece and having a ring-shaped portion, C, and clear space B, the ring portion being integral with the body, substantially as set forth.
- 10 2. A seal of metal or other composition having a ring-shaped portion integral with the

body and the body portion furnished with any given design or characters, and perforated to form a coupon or check, substantially as and for the purpose specified.

In testimony whereof I affix my signature in presence of two witnesses.

WILLIAM F. BEASLEY.
